UNITED STATES PATENT OFFICE.

JOE SPEIER, OF NEW YORK, N. Y.

CINDER-COLLECTING ATTACHMENT FOR LOCOMOTIVES.

No. 875,223.

Specification of Letters Patent.

Patented Dec. 31, 1907.

Application filed March 30, 1907. Serial No. 365,538.

To all whom it may concern:

Be it known that I, JOE SPEIER, a citizen of the Empire of Austria-Hungary, residing in New York, in the borough of Manhattan, county and State of New York, have invented certain new and useful Improvements in Cinder-Collecting Attachments for Locomotives, of which the following is a specification.

10 This invention relates to an improved attachment for locomotives by which the cinders and ashes which are carried off through the smokestack of the locomotive are collected and prevented from flying around towards the cars to the great annoyance of the passengers; and the invention consists of a cinder-collecting attachment for locomotives which comprises a closed casing divided by a transverse partition into two compartments, one compartment for collecting the heavier cinders and the other compartment for collecting the lighter cinders and ashes, the second compartment being partly filled with water for this purpose and connected 25 with the first compartment by a downwardly-extending conducting-pipe. The first compartment is connected by a pipe with a ventilating-fan driven by a suitable motor, which fan is connected with the smokestack, so that the force for carrying the products of combustion through the attachment and then to the atmosphere is produced.

In the accompanying drawings, Figure 1 is a side-elevation of a locomotive with my improved attachment for collecting cinders and ashes, Fig. 2 is a plan-view of Fig. 1, Fig. 3 is a vertical transverse section on line 3, 3, Fig. 2, and Fig. 4 is a vertical central section, drawn on a larger scale, of the ventilator, 40 showing its connection with the smokestack and cinder-collecting attachment.

Similar letters of reference indicate corresponding parts in the several figures of the drawings.

45 Referring to the drawings, *a* represents the boiler of a locomotive, *b* is the smokestack of the same, and *c* the casing of my improved cinder-collecting attachment which is supported adjacent to the front head of the 50 boiler on the platform in front of the same. The cinder-collecting attachment is preferably of such height that its upper part is on a level with the top part of the boiler.

The smokestack *b* is curved in a vertical 55 plane and connected at its outer downwardly-directed end with the casing *d* of a venti-

lator *d*, at the upper part of said casing. The curved smokestack enters the ventilator-casing at the center so that the products of combustion are forced through a curved pipe *e* 60 connected with the outside of the casing *d* and leading into the collecting-chamber or compartment of the casing *c*.

The casing *c* is divided into two chambers or compartments by an upright transverse 65 partition *c'* which is connected with a curved and downwardly extending pipe *f*, said pipe being located in the second compartment and extending below the level of a quantity of water in the same. The first compartment is provided with a deflecting-diaphragm *e'* for the products of combustion conducted through the pipe *e* in the upper part of the first compartment. A horizontal partition *c''* is arranged near the upper part 70 of the first compartment and provided with a funnel-shaped up-take *c''*, so that the products of combustion are conducted through the up-take into the upper part of the first compartment and from the same 75 to the downwardly-extending pipe *f* and into the second compartment. The heavier particles, such as cinders, are collected in the first compartment and removed from time to time from the same by means of a hinged 80 door *c''* arranged near the bottom of the same. The lighter cinders and ashes are delivered through the lower part of the pipe *f*, below the body of water, into the second compartment, while the products of combustion pass off through a chimney *g* that is arranged at the center of the second compartment. In the top of the first compartment is arranged a cover *h* so as to give access to the upper end of the conducting- 85 pipe *f* for cleaning the same.

The lower part of the second or water-compartment is provided with a tightly-closing side-door *c''* and with a discharge-cock *c''* for permitting the draining of the 90 water and the cleaning of the water-compartment from the impurities collected therein. At the upper part of the water-compartment is arranged a water-supply nipple *c''* having a stopcock, a hose being 95 attached to the supply-nipple for supplying a quantity of water to the water-compartment, which is provided, in addition thereto, with an indicator *i* by which the level of the water in the water-compartment is 100 indicated. This indicator consists of a float at the lower end and a rod which is guided

at the top part of the water-compartment, as shown in Fig. 3.

The ventilator is driven in any suitable manner by an electric motor m which is either placed on the shaft of the ventilating-fan or sidewise of the same, the power of the motor being transmitted in the latter case by a belt k and bevel gearing l from the shaft of the electric motor to the shaft 10 of the ventilator-fan. A register m^x is arranged in the bottom of the fan-casing so as to regulate the suction from the smokestack to the cinder-collecting attachment.

The attachment, connecting-pipes, fan- 15 casing, chimney, etc., are made preferably of strong sheet-steel so as to resist the wear and tear to which the same are subjected.

By drawing off the products of combustion with the cinders and ashes, and collecting 20 the cinders and ashes in the two compartments, merely the products of combustion are passed off through the chimney without causing any annoyance to the passengers in the train by cinders, while the suction by 25 the ventilating-fan serves to increase the draft in the boiler-flues.

Having thus described my invention, I claim as new and desire to secure by Letters Patent:

30 1. The combination, with a locomotive-boiler, of a cinder-collecting attachment provided with a transverse partition so as to form two compartments, one for collecting the coarser particles and the other

filled with water for collecting the finer particles, an up-take in the first compartment, a downwardly-extending conducting-pipe connecting the upper part of the first compartment with the lower part of the water-compartment, a ventilator supported on the 40 locomotive, a motor for operating the same, a curved smokestack connected with the center of the fan-casing, and a curved pipe for connecting the ventilator-casing with the first compartment of the cinder-collecting attachment.

2. In a cinder-collecting attachment for locomotives, a casing provided with a central partition, a supply-pipe connected with the smokestack for supplying the products 50 of combustion to the first compartment of the casing, a deflecting-plate below the lower end of the supply-pipe, a horizontal partition at the upper end of the first compartment provided with an up-take, a 55 downwardly-extending pipe connecting the upper part of the first compartment with the lower part of the water-compartment, and a chimney at the upper part of the second or water-compartment.

In testimony, that I claim the foregoing as my invention, I have signed my name in presence of two subscribing witnesses.

JOE SPEIER.
